(57) **CLAIM**

The ornamental design for a leash link clip, as shown and described.

DESCRIPTION

FIG. 1 is a front perspective view of a leash link clip showing my new design;

FIG. 2 is a side view thereof;

FIG. 3 is an opposite side view thereof;

FIG. 4 is a front view thereof;

FIG. 5 is a back view thereof;

FIG. 6 is a top view thereof;

FIG. 7 is a bottom view thereof;

FIG. 8 is another front perspective view thereof;

FIG. 9 is a back perspective view thereof;

FIG. 10 is another back perspective view thereof; and,

FIG. 11 is another side view thereof.

In FIGS. 8, 10, and 11, the claimed design is shown in an alternative position with the leash link clip depicted in an opened configuration.
